UNITED STATES PATENT OFFICE

2,237,673

ELECTRIC CLOCK

Richard P. Landgraf, Chicago, Ill.

Application July 24, 1939, Serial No. 286,116

6 Claims. (Cl. 58—26)

My invention relates in general to electric clocks. It relates more in particular to a combination with an electric clock of improved means for indicating when the clock is running.

Electric clocks propelled by small synchronous motors are either of the self-starting or non-self-starting type. In general, the latter is preferred. Self-starting clocks have an advantage in that if the current is interrupted for a short period of time, they will again start themselves without human agency. They have a disadvantage in that they may be found to be running and still show the incorrect time. It is customary, therefore, to place some indicating means on a self-starting clock to show whether or not the current has been interrupted. If it has been interrupted, the user of the clock finds it necessary to reset it.

If the non-self-starting type of clock is operated on a source of alternating current which is interrupted, the clock stops permanently. This compels the user of the clock to start it again manually, and in so doing he will set it to the right time. Although certain advantages are possessed by the non-self-starting type of clock in that if the clock is running at all it will always show the right time, it is not always easy to determine at a glance whether or not the clock is running. As a rule, some type of flasher mechanism is employed, usually comprising a varicolored disc rotatable with one of the mechanical shafts and visible through a small aperture in the face of the clock. Even when the light is good, it is sometimes necessary to look closely to determine whether or not the flasher is operating and when the light is bad or the observant is some distance away, it is very difficult to determine whether or not the clock is in operation.

According to the principal object of my invention, it is the provision of an improved means for determining when the clock is operating.

Another object is the provision of such a means which may be employed on either a self-starting or non-self-starting type of clock.

Another object is to utilize a pendulum which tends to swing of its own accord, wherein a small increment of power is employed to maintain the pendulum in operation.

Another object is the provision of improved means for employing a pendulum mechanism with an electric clock whereby to tell an observer at a glance whether or not the clock is in operation.

Other objects and features of the invention

will be apparent from the following detailed description taken with the accompanying drawing, wherein

Fig. 1 is a face view showing a portion of the clock assembled without the casing;

Fig. 2 is a side elevational view thereof;

Fig. 3 is an enlarged fragmentary sectional view taken on the line 3—3 of Fig. 1; and

Fig. 4 is an enlarged view taken on the line 4—4 of Fig. 3.

Looking at Fig. 3, I show a usual type of dial face 10, hands 11 and 12, and a relatively small pendulum 13 mounted to swing on the axis of the hands as a pivot. The pendulum is commensurate with the hands in size and may be finished a relatively bright color so that it may be at least as noticeable or possibly more noticeable than the hands themselves. The clock face shown in the drawing is a relatively large one as may be readily determined by comparing it with the size of the synchronous motor and movement in Fig. 2; consequently the pendulum mounted entirely within the confines of the dial face is relatively large enough for my purpose. It will be understood, however, that I may mount the pendulum differently, particularly when a relatively small face is employed on the clock. I shall refer briefly to the mechanism as shown in Fig. 2 to illustrate a preferable form of drive for continuously imparting sufficient power to the pendulum to maintain it in operation.

An alternating current coil 14, adapted to be supplied with current from a suitable source, has a core 16 connected with pole pieces 17 (the drawing shows only one, although two are customarily used) forming the stator of the motor. A rotor shown in dotted lines at 18 is connected to a rotor shaft 19. This rotor shaft carries a pinion 20 meshing with a gear 22 carried on a shaft 23.

This shaft 23 supports a worm 24 which, through a suitable gear train including the usual twelve to one time train, drives the hands at proper differential speed. The hands are mounted on the usual time shaft 26 and stud 27 customary in the art.

Now as to the operation of the pendulum, I employ a sleeve 28 which projects through the dial face and is journaled on the time stud 27. The portion of the sleeve 28 extending beyond the face 10 has a pendulum 13 secured thereto. Within the mechanism housing, however, I support an arm 29 provided with a longitudinal end slot 31. A relatively small crank 32 carried on the shaft 23 engages in this slot and as the shaft 23 rotates carrying the crank 32 with the arm 29

and sleeve 28 are reciprocated about the time stud 27, thus also imparting a reciprocating pendulum-like swing, to the pendulum 13.

The pendulum may, of course, be made to swing at any selected frequency. In the design of clock mechanism in which I employ my pendulum, the shaft 28 makes one complete rotation every second. Consequently, the period of the pendulum is also one second; that is to say, it takes one second for it to make a complete swing back and forth from one side to the other. By selecting a pendulum whose natural period is substantially one second, the pendulum tends to move itself and there is very little power required to be imparted to it through the crank 15 mechanism described.

Although I describe my invention in detail to permit those skilled in the art to practice it, it is obvious that I am not restricted to the particular form of the invention shown, but am 20 limited only by the scope of the appended claims.

What I claim as new and desire to protect by Letters Patent of the United States is:

1. In an electric clock, a synchronous motor, a time indicating mechanism, a time train mechanism receiving movement from the synchronous motor and connected to impart time movement to the time indicating mechanism, a dial face disposed between the time indicating mechanism and the time train mechanism, a pivoted sleeve 25 extending through the dial face, a pendulum secured to the sleeve at one side of the dial face, an arm secured to the sleeve at the opposite side of the dial face, said arm having a longitudinal slot therein, and a crank secured to a shaft forming a part of the time train mechanism, said crank extending into said slot whereby rotation of the shaft imparts a pendular movement to said pendulum through said arm and sleeve.

2. In an electric clock, a synchronous motor, a time indicating mechanism, a time train mechanism, receiving movement from the motor and imparting time movement to the time indicating mechanism, a dial face, a pivoted sleeve extending through the dial face, a pendulum secured to the sleeve on one side of the dial face, an arm secured to the sleeve on the opposite side of the dial face, said arm having a longitudinal slot therein, a shaft forming a part of the time train mechanism and having gear connections 40 to cause the same to make one complete rotation

every second, and a crank secured to said shaft and extending into said slot.

3. In an electric clock, a dial face, a synchronous motor, a time train mechanism driven by said motor and including a motor shaft and time stud, minute and hour hands secured respectively to the said time shaft and stud, a sleeve journaled on said stud and extending through the dial face, a pendulum secured to the sleeve and visible against said dial face, an arm secured to said sleeve, said arm having a slot therein, and a crank secured to a shaft forming a part of the time train mechanism, said crank extending into the slot in said arm.

4. An electric clock as defined in claim 3, wherein said shaft forming a part of the time train mechanism rotates at a speed of one revolution per second.

5. In an electric clock, a dial face, a synchronous motor, a time train mechanism driven by said motor, and including a shaft and sleeve extending through said dial face, said shaft and sleeve carrying hour and minute hands respectively, a sleeve extending through said dial face concentric with said shaft and journaled on said first-mentioned sleeve, a pendulum member mounted on the said last-mentioned sleeve and against the said dial face, a slotted arm on the last-mentioned sleeve behind said dial face, and a crank secured to a rotating shaft forming a part of the time train mechanism, said crank extending into said slot of said arm whereby to cause reciprocation of said sleeve and pendulum.

6. In an electric clock, a dial face, a synchronous motor, a time train mechanism driven by said motor, and including a shaft and sleeve extending through said dial face, said shaft and sleeve carrying hour and minute hands, respectively, a second sleeve extending through said dial face concentric with said shaft and journaled on said first-mentioned sleeve, a pendulum mounted on said second sleeve and against said dial face, a crank secured to a rotating shaft forming a part of the time train mechanism, an arm carried by said second sleeve and extending toward said crank, and mechanical means forming a connection between said arm and crank whereby to impart oscillatory motion to said arm and pendulum.

RICHARD P. LANDGRAF.
